UNITED STATES PATENT OFFICE.

CHARLES F. SCHWENNKER, OF SCHENECTADY, NEW YORK, ASSIGNOR TO GENERAL ELECTRIC COMPANY, A CORPORATION OF NEW YORK.

ELECTRIC SWITCH.

Application filed June 17, 1924. Serial No. 720,686.

To all whom it may concern:

Be it known that I, CHARLES F. SCHWENNKER, a citizen of the United States, residing at Schenectady, in the county of 5 Schenectady, State of New York, have invented certain new and useful Improvements in Electric Switches, of which the following is a specification.

My invention relates to circuit controlling 10 means and particularly to means for the control of high potential circuits comprising a main switch which for example may be of the fluid break type, and an isolating or disconnecting switch.

15 One object of my invention is to provide an improved actuating mechanism for said switches whereby they may be caused to close and open in a definite manner relative to each other.

20 Another object is to provide an improved construction of isolating or disconnecting switch in which no flexible connections are required for connecting it with the main switch.

25 A further object is the provision of improved means whereby the disconnecting switch may be locked either in closed position or in open position without affecting the normal operation of the main switch.

30 My invention will be better understood from the following description taken in connection with the accompanying drawing, and its scope will be pointed out in the appended claims.

35 In the drawing, Fig. 1 is an elevation of the main switch and the disconnecting switch together with the operating mechanism therefor according to my invention, the switches being shown in open circuit position; Fig. 40 2 is a similar view with the switches in closed circuit position; and Fig. 3 is a detail of the disconnecting switch.

The main switch 1 is illustrated, for example as a common form of oil break switch, 45 the tank of which is indicated only by dotted lines. The cover 2 carries the insulator bushings 3 which support the stationary contacts 4 at their lower ends. The yoke 5 which carries the movable contacts is mounted on the lower end of the operating rod 6 which slides through the cover 2 and to which is pivoted the operating lever 7. This lever is connected by links 8 to bell crank 9 whose actuation is effected by means which 50 will be described later.

The conductors which pass up through the cover 2 within the insulator bushings 3 terminate in blocks 12 to which are firmly secured extensions 13 in the form of straight rods or bars of copper or other good conducting material forming fixed contact members. Above the oil switch extends a support 14 for the two stationary contacts 15 of the disconnecting switch. Each of these contacts, as shown more clearly in Fig. 3, has a tapering or wedge-shaped lower portion, the upper portion being secured to the support 14 by a bolt 16. For convenience in attaching leads thereto the contacts are shown provided with terminals 17. The movable portion of the disconnecting switch comprises a crosshead 18 made up of two strips 19 and 20 preferably of insulating material which are rigidly secured together and to which is pivoted the bifurcated operating lever 21. Each strip 19 and 20 carries on its inner face a plate 22 having ears 23 and on these ears are pivotally mounted the contact members 24, suitable stops 25 being provided to limit the pivotal movement of these members for the purpose hereinafter explained. The contact members themselves each comprise a plate 26 having a contact tip 27 at each end thereof. A good electrical connection between the tips of each plate is provided by a flexible current carrying conductor or pigtail 28, and a spring 29 at the opposite side of each plate provides the necessary resilience. When the switch is in its closed position as shown by Figs. 2 and 3 90 the upper ends of two opposed contact members are spread apart by their engagement with the tapered stationary contact 15, causing the opposite ends of those members to firmly engage the upper end of the corresponding extension 13. A low resistance connection is thereby provided between each stationary contact 15 and a terminal of the oil switch. When the disconnecting switch is to be opened, the lever 21 is released and the crosshead and contact members move downwardly out of engagement with the contacts 15. The contact members are now free to rock on their pivots by gravity until checked by the stops 25, sufficient movements being thereby permitted to avoid frictional contact between the extensions 13 and the lower tips 27. Guide members 30 secured to the strips 19 and 20 at each end of the crosshead 18 slide against the extensions 13. 100 105 110

The lever 21 is pivoted to the frame 31 by pin 32 and connected also between this lever and the frame are the spring 33 and the dashpot 34. Both the oil switch and the disconnecting switch are actuated through the instrumentality of a toggle mechanism comprising the links 36 and 37. Link 36 is a plain link pivoted at its upper end to lever 21 and having a slot 38 for the pin 39 at its lower end. Link 37 is pivoted to the frame at 40 and is provided with one arm 41 carrying a roller 42 at its extremity and with another arm 43 to which are operatively connected toggles 44 and 45. Toggle 45 is retained slightly overset when the switches are closed and is adapted to be struck a sharp blow by the plunger 46 of a solenoid when the switch is to be tripped. A switch operating solenoid raises the plunger 48 and in engaging the roller 42 shifts the toggle links 36 and 37. The tripping mechanism comprising the toggles 44 and 45 and the operating solenoid is that in common use and further explanation thereof will therefore not be given.

Connected with the pivot pin 39 between links 36 and 37 is the adjustable link 50 having a slot 51 through which passes the pin 52 carried by the bell crank 9. A link 53 having a slot to receive the pin 52 is attached to one end of a tension spring 54 whose opposite end is pivotally connected to the frame. This spring is tensioned when the switches are closed and is provided for the purpose of giving the oil switch a quick initial opening movement.

It will be noted that in accordance with this construction the main or oil switch is operatively connected with the common connection 39 between the toggle links 36 and 37 and the disconnecting switch is operatively connected with the opposite end of toggle link 36. It will also be seen that as a result of this toggle arrangement and the pin and slot connection between the toggle links, the oil switch when tripped opens with a rapid movement while the disconnecting switch under the retarding influence of the dashpot 34 moves to open position relatively slowly, thereby insuring the complete opening of the circuit by the oil switch before the contacts of the disconnecting switch separate. In the closing of the switch as the dashpot is not effective and by reason of the buckled relation of the toggle links 36 and 37 the initial upward movement of the link 36 is comparatively rapid. The disconnecting switch thus moves to closed circuit position first and subsequently upon further movement of the toggle links the circuit is finally and completely closed by the oil switch.

Occasion sometimes arises, as for instance, when the oil switch is to be inspected or repaired, when it is desirable to be able to lock the disconnecting switch in open circuit po-

sition without affecting the normal operation of the oil switch. I have provided means for so locking the disconnecting switch in open circuit position which comprises a separate opening 56 for the reception of pin 32 by which the lever 21 is fulcrumed. By removing pin 32, raising lever 21, and inserting the pin in the opening 56 and through the lever, the fulcrum point of the lever is raised to such an extent that the switch closing operation of the toggle links will not cause the disconnecting switch to close. Furthermore a stop pin 57 will engage lever 21 and prevent it being raised by hand to close the switch controlled thereby when the fulcrum pin has been transferred to the upper opening. Suitable key controlled locking means, as for example a padlock, may of course be provided for preventing the unauthorized removal of the pivot pin 32 from either opening. I have also provided means for locking the disconnecting switch in closed circuit position. This comprises a projection 58 on lever 21 and a member 59 loosely pivoted on the frame at 60. Member 59 has a portion adapted to engage the projection 58 and has two openings therein, either one of which may receive the pin 61 whereby it may be held either in the position illustrated where it does not interfere with the free movement of lever 21 or in its other position, not illustrated, whereby engagement with the projection 58, lever 21 will be held against downward movement. Pin 61 may also be secured in either position by suitable key controlled locking means, such as a padlock, to prevent unauthorized removal thereof.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States is:—

1. A circuit controlling mechanism comprising a main switch, a disconnecting switch, and common actuating means for said switches, said means comprising toggle links, means connecting said main switch with the common connection between said toggle links and means connecting said disconnecting switch with the opposite end of one of said links.

2. A circuit controlling mechanism comprising a main switch, a disconnecting switch, a pair of toggle links, means for pivotally mounting the outer end of one of said links, means for operatively connecting the outer end of the other of said links with said disconnecting switch, means for operatively connecting the common connection

between said links with said main switch and means for moving said pivotally mounted link.

3. A circuit controlling mechanism comprising a main switch, a disconnecting switch, a lever for moving said disconnecting switch, a pair of toggle links having the outer end of one link pivoted to said lever and having a pin and slot connection at their adjacent ends, means operatively connecting said main switch to said links at said pin and slot connection, and means whereby the fulcrum of said lever may be shifted to render said lever non-responsive to the operation of said toggle links.

4. In combination, a main switch, fixed contact members secured to the terminals thereof, fixed contacts spaced from said contact members, and a movable member having contacts adapted to slide on the fixed contact members and to engage the spaced fixed contacts.

5. In combination, a main switch of the fluid break type, having terminals projecting therefrom, conducting extensions secured to said terminals, and a disconnecting switch comprising fixed contacts, a crosshead having resilient members slidably engaging said extensions and having contacts adapted to engage said fixed contacts.

6. In combination, an oil switch having terminals extending from the cover thereof, a conducting rod secured to each of said terminals, and a disconnecting switch comprising stationary contacts, a crosshead, an operating lever pivoted thereto, arms carried at opposite ends of said crosshead for slidably engaging said rods, and contacts carried by said crosshead for engaging said stationary contacts and said rods.

7. In a switch, a tapering fixed contact, a conducting rod spaced therefrom, a movable contact member pivotally mounted at a point intermediate its ends and means for moving said contact member longitudinally of said rod whereby the engagement of one end of said member with said tapering fixed contact rocks said member to cause the opposite end thereof to engage said rod.

8. In a switch, a tapering fixed contact, a fixed conducting rod spaced from and in alignment with said contact, a contact sup-

porting member, a plurality of movable contact members pivoted to said supporting member and arranged on opposite sides of said tapering contact and said rod whereby when said supporting member is moved in a direction to cause one end of each of said movable contact members to engage said tapering contact, the opposite ends of said contact members are caused to engage said rod and when said supporting member is moved in the opposite direction said contact members release their engagement with both the tapering contact and the rod.

9. A circuit controlling device comprising a main switch having terminals provided with extensions, a disconnecting switch comprising a crosshead having contact members adapted to make sliding contact with said extensions, fixed contacts also engaged by said contact members, an operating lever pivotally connected to said crosshead, common operating means for said main switch and said disconnecting switch comprising toggle links, said main switch being operatively connected to the common connection between said toggle links and the operating lever of said disconnecting switch being connected to the opposite end of one of said links, and switch actuating means for moving the other of said links.

10. A circuit controlling device comprising a main switch, a disconnecting switch associated therewith and comprising a slidably mounted crosshead, an actuating lever pivoted thereto, a toggle mechanism for actuating both of said switches comprising a pair of links having a pin and slot connection therebetween, means operatively connecting said main switch and the connection between said toggle links, said actuating lever being connected to the opposite end of one of said links, and an adjustably mounted member adapted to be secured in a position to engage said lever to prevent opening of said disconnecting switch, said pin and slot connection between the toggle links serving to permit independent operation of said main switch.

In witness whereof, I have hereunto set my hand this 16th day of June, 1924.

CHARLES F. SCHWENNKER.
